WOMAN'S PETTICOAT

Lenore B. Cooley, New York, N. Y.; First National
Bank of Santa Fe, executor of said Lenore B.
Cooley, deceased.

Application November 23, 1946, Serial No. 711,858.

3 Claims. (Cl. 2-224)

1.

This invention relates to women's undergarments and particularly to petticoats.

One object of the invention is a novel and improved petticoat which is characterized by its functioning as a panty as well as a petticoat, by its design features simulating a petticoat effect notwithstanding the panty functioning, by giving marked freedom of body and leg movement by its form fit and by the economy with which the garment may be manufactured in quantity production.

Further objects of the invention will herein-after appear.

For a better understanding of the invention reference may be had to the accompanying drawings forming a part of this application, wherein

Fig. 1 is a perspective view of a petticoat embodying the invention;

Fig. 2 is a sectional view along the line 2-2 of Fig. 1;

Fig. 3 is a sectional view along the line 3-3 of Fig. 1;

Fig. 4 is a view of a pattern of one of the panels of the garment;

Fig. 5 is a view of another of the patterns or panels of which the garment is made; and

Fig. 6 is an exploded view of the patterns or panels utilized in the making of the garment.

Referring to the drawings, the garment is indicated at 1 in Fig. 1. The waistline of the petticoat is indicated at 2 and any suitable trimming 3 may be provided if desired at the bottom edge of the petticoat.

The garment is made of six vertical panels, two side panels *a* adjoining front panels *b*, *b'* and adjoining back panels *c* and *c'*. The panels *a* are identical and the panels *b*, *b'*, *c*, *c'* are identical, one of the panels *a* being shown in Fig. 4 and one of the front and back panels being shown in Fig. 5. The panels *b*, *b'*, *c*, *c'* form the waistline 2 of the garment, each of these panels being provided at its upper end with a circumferentially and laterally tapering part 4. The parts 4 of the panels *b* and *c* are attached together on the side of the garment and similarly the parts 4 of panels *b'* and *c'* are attached or sewn together on the opposite side to form the side halves of the waistline. In the particular embodiment shown the tapering parts 4 are formed of triangular shape having outer straight lined edges 5 meeting at an acute angle with the upper edges 4' of the panels. Thus the straight edges 5 form a part of the side edges of the panels corresponding to the sides upon which the parts 4 are located and the side edges 5 merge into or

meet the outer side edges 6 of the inner panels and these outer side edges 6 in the particular embodiment shown are straight edges. Each of the panels *b*, *b'*, *c*, *c'* gradually widens beginning at the lower portions of the triangular parts 4 to form an intermediate gradually widening part 7 and a lower part 8 whose width approximates the width of the upper end edge 4' of the panel. The dividing lines of these panel portions 4, 7, 8 are indicated by dotted lines 7' and 8'. The inner edge of each of these panels formed of the portions 4, 7 and 8' is formed of a continuous line 9 extending downwardly about two-thirds of the distance or through the depth of the parts 4 and 7 and of a lower line or edge 10. These lines 9 and 10 which together form the inner edge of one of the inner panels are curved to form concave edges. The inner edges 9 of the panels *b* and *b'* are sewn together to form the seam 9' of the garment and likewise the curved edges 9 of the panels *c* and *c'* are sewn together to form a seam similar to the seam 9' on the back of the garment, a suitable zipper fastener 20 or the like being a continuation of the rear seam 9'. In the particular embodiment shown the width of portion 8 of the panel is a little more than twice the width along the line 7' and is slightly less than the width at the top edge, as indicated by the proportions 9y, 4y and 10y.

The lower parts 8 of the panels *b* and *c* are sewn together along the lines 10 to form the seam 10' and likewise the curved edges 10 of the panels *b'* and *c'* are sewn together to form a similar seam 10'. The panels *a* are observed to have tapered upper parts 11 shaped to fit into the angles formed between the upper parts 4 of the front and back panels *b* and *c* and the front and back panels *b'* and *c'* respectively. For this purpose the upper parts 11 of the panels *a* are tapered in an upward direction to have straight edges 11' which fit on to and are sewn to the straight edges 5 of the front and back panels to form the inclined straight seams 12. The panels *a* are gradually increased in width toward the lower end and in the particular embodiment shown the panel *a* is substantially one-half greater at the bottom than at the top as indicated by the lines 19y and 12½y. The side edges 13 of each panel *a* are sewn to the outer edges 6 of the inner panels to form the seams 14 both front and rear. The edges 5 of the portions 4 of the central panels are a little longer than the complementary edges 11' of the side panels to form a folded edge at the top of parts 4 of the central panels.

The points where the seams 12 and 14 meet are indicated at 15 and these four points 15, two on the rear and two on the front define a plane which passes at or closely in the vicinity of the hip bone of the wearer and the panels are formed to fit this purpose. Also the relative proportions of the widths of the panels in this plane defined by the points 15 are roughly three for the panels *a* and one each of the panels *b*, *b'*, *c* and *c'* as indicated in the sectional view indicated in Fig. 2. 10 Also the inner panels *b*, *b'*, *c* and *c'* are formed of fabrics which are cut with the weave while the side panels *a* are cut on the bias. The relative proportions of the widths of the panels at the bottom may vary within limits with respect to 15 each other but I have found particularly good results with the widths of the panels *a* at the bottom equal to roughly twice the width of each of the inner panels at the bottom.

It is to be observed that in this garment the upper parts of the inner panels *b*, *b'*, *c* and *c'* form entirely the waistline, the central upper sections 11 of the panels *a* joining the tips of the tapered parts 4 of the panels. The upper parts of the inner panels constitute a gradually decreasing proportion downwardly of the body of the garment between the waistline 2 and the plane through the points 15.

The garment of this invention by reason of the design and structure above described has a number of advantages. These include among others the particular structure and design of the front and back panels *b*, *b'*, *c* and *c'* together with their correlation with the bias cut side panels *a* which prevents undesirable drooping or sagging of the crotch and the bias cut side panels give the desired fullness of the petticoat at the bottom without extra gathers at the top to thicken the body and the crotch of the garment is concealed by the lower parts of the inner panels tending to fold over each other due to the particular design and structure of the inner panels and due in part also to the side panels *a* which hang in a manner to make the seams 14 substantially vertical, thereby accentuating the folding over of the lower parts of the inner panels, to conceal the dividing line between the side halves of the petticoat at the bottom. The lower portions 3 of the central panels have a depth sufficient, together with the concave edges 9 and 10 and the fullness of the lower part of the garment, to provide complete simulation of petticoat lines without division, and a depth which at the same time is small enough together with the fullness to provide at the bottom a divided petticoat, each division of which is sufficiently full to permit free and easy use for sanitary purposes, without the necessity of removal from the waist and no unbuttoning or unfastening being required for these purposes. For example, the crotch line 3' of the garment is approximately halfway from the crotch line 25 of the wearer to the bottom of the petticoat, where the bottom edge is in the vicinity of the knee in the embodiment shown and I have found that for a medium size garment a circumference of roughly 32 to 34 inches for each divided part at the bottom is quite satisfactory.

I claim:

1. A petticoat embodying front, back and side panels, each of the front and back panels comprising two mating parts, each part having a width at the waistline of approximately one-

fourth the waistline of the garment and having a side edge to join its mating side panel composed of two straight edges disposed at an obtuse angle, the other side of each part having a concave curved side edge extending downwardly and having a shorter curved edge extending downwardly from said concave edge to the bottom, the shorter curved edges of the front panel parts at the bottom being fastened respectively to the similar parts of the back panel thereby providing inside leg seams, said side panels being tapered from bottom to top and the top tapering sharply to a point at the waistline to match the two straight edges at each side of the corresponding front and back panels which are disposed at an obtuse angle.

2. A woman's undergarment providing a combined panty and petticoat, said undergarment comprising six panels and having its front and back body and leg portions and its waist formed of two pairs of front and back panels and its side portions formed mainly of two side panels, the upper edges of the front and back panels forming the waist line, the front and back panels of each pair being formed in duplicate shape and each panel of both pairs having an upper portion tapering on one side to a point in the waistline with the points of the front pair adjacent to the points of the back pair to form the waistline, each panel of the front and back pair having concavely curved inner edges extending from the waistline downwardly to a crotch point, means to join said concavely curved inner edges together, each panel of the front and back pair having a short concave curved edge extending from the crotch point to the bottom, said last named edges being joined respectively to similar edges formed on the other pair thereby to provide an inside leg seam, the outer edges of the front and back panels being formed of straight edges, each panel having two straight angularly disposed edges, one providing said taper to a waistline point, and the other edge extending throughout the intermediate and bottom portions of the panels, a pair of side panels, each of said side panels tapering from the bottom upwards of the panel and the undergarment, each of said side panels having more abruptly tapering upper portions to fit the two front panels and the rear panels, said two pairs of front and back panels gradually increasing in width in a downward direction to provide a form fit about the waist and just below the waist of a wearer and means for connecting the outer edges of the front and back panels with the adjacent edges of the side panels.

3. The undergarment of claim 2 in which said side panels are cut on the bias and the front and back panels are cut with the weave.

LENORE B. COOLEY.
